UNITED STATES PATENT OFFICE.

WARD W. DENISTON, OF WASHINGTON, DISTRICT OF COLUMBIA.

COLLAR OR TIE ADJUSTER.

SPECIFICATION forming part of Letters Patent No. 295,526, dated March 25, 1884.

Application filed December 7, 1883. (No model.)

To all whom it may concern:

Be it known that I, WARD W. DENISTON, a citizen of the United States, residing at Washington, in the District of Columbia, have 5 invented certain new and useful Improvements in Collar and Tie Adjusters, &c.; and I do hereby declare the following to be a full, clear, and exact description of the invention, such as will enable others skilled in the art to which 10 it appertains to make and use the same.

My invention relates to a device for holding and securing a collar to a band of a shirt, and at the same time securing the necktie, and preventing the same from slipping over 15 the top of the collar, all of which will be more fully hereinafter specified, and pointed out in the claims.

In the accompanying drawings, Figure 1 represents a perspective view of the top of 20 the shirt provided with a band and having a collar thereon, my device being shown on the side of the band. In this view the necktie is omitted. Fig. 2 is a vertical section of the shirt-band, collar, and necktie, and my 25 device. Fig. 3 is a perspective view of the device, a part of the central strip being broken away to show the band-engaging teeth.

Like letters indicate like parts throughout the several views.

30 A, B, and C are three flat parallel integral pieces, and constituting the main part or body of the device.

The letter A represents the central strip, and B the downwardly-projecting inside strip. 35 a is the curved top part of the device, and unites the strips A and B.

b are teeth on the edge of the right-angle projection on the bottom of the strip B. These teeth are adapted to engage the inside of the 40 collar-band.

C is the outside strip.

d is the curved lower end, and unites the parts A and C.

D D are the outward downwardly-projecting spurs on the piece C. These spurs are struck out of the metal constituting the device. They are intended to engage the necktie, which lies against them, and prevent the same from slipping up or passing over the top 50 of the collar.

e are teeth on the inner right-angled projection on the top of the strip C. These teeth are adapted to engage the outside of the collar and secure it, whereby the collar is prevented from slipping above the shirt-band. 55

F represents the collar; G, the shirt-band, and H the necktie.

The object of this invention is to secure the collar in a fixed position in relation to the shirt-band, and at the same time secure the 60 necktie in a fixed position in relation to the collar—that is to say, the device is intended to secure the collar and the necktie in a fixed relative position on the shirt-band. It is a well-known fact that considerable trouble is 65 experienced in keeping a collar and necktie in their proper position about the shirt-band. My invention obviates this difficulty by a simple, cheap, and effective device.

The operation of the device is as follows: 70 The shirt-band is inserted between the strips A B. This can be done by springing out the strip B, whereby the teeth of the lower projection thereof are held away from the band until the device is drawn down on said band 75 to the desired point. By this means the device is firmly secured to the band. Then by springing out the top part of the strip C the collar is inserted between said strip and the strip A. Then by letting go of the part C the 80 teeth e of the upper right-angled projection thereof engage the outside of the collar. After the collar and shirt-band have thus been united, the necktie may be placed about the collar and over the outer surface of the part C of the device. The spurs D D on the part C will then 85 prevent the necktie from rising as well as passing around the neck. It will thus be seen that the device holds the collar and necktie in a fixed relative position. 90

The device is preferably constructed of resilient metal, with an inward tendency of the teeth b and e. The normal position of these teeth is inward against the sides of the portion A. The teeth are, however, easily sprung 95 out by hand in engaging the device to the band and securing the collar.

Having thus described my invention, I claim as new and desire to secure by Letters Patent—

1. A device formed of the strips A B C, the 100

parts B C having inward end projections provided with teeth, whereby the collar may be secured to the band of the shirt, substantially as described and specified.

5. 2. A device formed of the strips A B C, the parts B C thereof being provided with inward end projections having teeth *b e*, respectively, the part C having spurs *D D* upon its outer side, substantially as described, and for the purpose set forth.

3. A device for securing a collar to a shirt-band, consisting of a single piece of metal

curved at *a d*, whereby the parts A B C are formed, the outer ends of the parts B C having inturned pointed ends, for the purpose of 15 engaging or clamping the shirt-band and collar, in the manner and for the purpose set forth.

In testimony whereof I have affixed my signature in presence of two witnesses.

WARD W. DENISTON.
